MECHANISM FOR TURNING ON A PORCH
LIGHT WHEN A DOORBELL IS RUNG

James E. McNeil, Alhambra, Calif.

Application December 8, 1948, Serial No. 64,166

4 Claims. (Cl. 315—76)

1

My invention relates to mechanism for turning on a porch light when a doorbell is rung.

The turning on of the porch light at the time that the doorbell is rung will enable the occupant of the house to more clearly see who is ringing the bell before they open the door.

Another object of this invention is to provide illumination for a returning householder to see the keyhole and insert his own key in the door.

Another feature of this invention is that it may be disconnected during the daytime, or when the occupants are out of town, so that ringing of the doorbell during those periods will not turn on the light.

Other objects and advantages of my invention will be apparent from the following description and claims, the novelty consisting in the features of construction, combination of parts, the unique relations of the members and the relative proportioning, disposition and operation thereof, all as is more completely outlined herein and particularly pointed out in the appended claims.

In the accompanying drawing, forming a part of this present specification I have provided a diagrammatic showing of my invention, together with sectional showing of the mechanism to actuate the electrical circuits.

Referring to the drawings, the preferred embodiment of my doorbell light comprises an outside push button 10, a bell 12 and a porch light 14 with the connecting mechanism described below.

The outside push button 10 is adjustably connected to a plunger 16 which is arranged to act against the force of a spring 18 mounted in a suitable housing 20. The outer end of the housing 20 is closed by a plug 22 which is mounted flush with the outer end of the housing 20.

Thus the distance between the outer face of plug 22 and the under surface of push button 10 may be varied by the distance push button 10 is screwed into plunger 16 to fit the varying thickness of house walls or plaster coatings.

The other end of plunger 16 is attached to a striker 24. When the outside push button 10 is depressed against the force of spring 18, it causes striker 24 to contact a movable contact member 26 and force it into contact with a stationary contact member 28. Contact of these members 26 and 28 with each other closes the electrical circuit which causes the bell 12 to operate. When the operator withdraws his pressure from the outside push button 10, the spring 18 pulls back the plunger 16 and with it the striker 24 thus permitting the movable contact member 26 to

spring back out of contact with the stationary contact member 28. This stops the bell 12 from ringing.

When the outside push button 10 and its attached plunger 16 and striker 24 are depressed, it also causes striker 24 to strike control lever 30 which is attached to rotatable shaft 32. Spring means 34 assure that, when striker 24 strikes control lever 30 and moves it a slight distance, rotatable shaft 32 is rotated sufficiently to cause manual switch contact 36 which is integrally attached to rotatable shaft 32 to move out of contact with manual switch 37 and to cause automatic switch contact 38 to move into contact with automatic switch 39.

In the position shown in the drawings, manual switch contact 36 is in contact with manual switch 37 thereby closing the circuit between wires 40 and 42. In this position it is possible to actuate switches 44 and 46 from the open position shown to a position where they establish a contact between wires 40 and 42 thereby turning on light 14 by the manual operation of switches 44 and 46 which thereby establishes contact between wires 48 and 50 through light 14.

On the other hand, wires 52 and 54 may be connected by the closing of switch contact 38 against automatic switch 39 when outside push button 10 is depressed as pointed out hereinabove.

Manual switches 44 and 46 may be rotated so that they contact points 56 and 58 to establish contact and circuit connection between wires 40 and 42 when manual switch contact 36 is in contact with manual switch 37. Also manual switches 44 and 46 may be rotated out of contact with points 56 and 58 and into contact with points 60 and 62 to establish a circuit between wires 52 and 54 when automatic switch contact 38 is closed against automatic switch 39. In performing these movements manual switches 44 and 46 rotate on their pivots 64 and 66.

After light 14 has been turned on by depressing outside push button 10 in the manner described hereinabove, if it is desired to return the mechanism to the condition in which it was before outside push button 10 was depressed, the occupant of the house can depress inside push button 68 which is connected to plunger 70 that is mounted against the action of spring 72 in housing 74. A suitable plug 76 closes the opening of housing 74 and fits flush against the inner wall of the house. A striker 78 is integrally mounted at the other end of plunger 70.

Thus when inside push button 68 is depressed

against the action of spring 72, it causes striker 78 to strike control lever 30 and rotate it and rotatable shaft 32 to its former position. This will cause automatic switch contact 38 to move out of contact with automatic switch 39 and will cause manual switch 36 to move into contact with manual switch 37 in the position shown in the drawings accompanying this application.

Thus it will be seen that depressing outside push button 10 will cause bell 12 to ring and light 14 to be lit when manual switches 44 and 46 are closed into contact with points 60 and 62. When this is done light 14 will remain on until the automatic mechanism is reset by depressing inside push button 68, or the system is changed from automatic to manual by moving manual switches 44 and 46 out of contact with points 60 and 62 and into contact with points 56 and 58. In the latter case of course, push button 68 must be depressed to cause manual switch contact 36 to come into contact with manual switch 37 and place the system on a manual operation basis.

Of course, other uses for my mechanism will be apparent and my invention is not limited to the particular use shown and described in this application.

It is to be understood that the form of my invention herein shown and described is my preferred embodiment and that various changes in the shape, size and arrangement of parts may be resorted to without departing from the spirit of my invention, or from the scope of the appended claims.

I claim:

1. An electric light and bell system comprising a shaft rotatable from a first position to a second position, an arm secured to said shaft, a first push button and a first striker positioned to engage said arm and rotate said shaft from said first position to said second position when said first push button is pressed, a second push button and a second striker positioned to engage said arm and rotate said shaft from said second position to said first position when said second push button is pressed, a bell, a bell circuit, a normally open switch in said bell circuit positioned to be actuated by said first striker to close said bell circuit while said first push button is depressed, a lamp, a lamp circuit and a switch contact secured to said shaft and positioned to close said lamp circuit when said shaft is in said second position.

2. A system as described in claim 1 in which is included means for independently closing said lamp circuit while said shaft is in first position.

3. An electric switch system comprising a shaft rotatable from a first position to a second position, an arm secured to said shaft, a first push button and a first striker positioned to engage said arm and rotate said shaft from said first position to said second position when said first push button is pressed, a second push button and a second striker positioned to engage said arm and rotate said shaft from said second position to said first position when said second push button is pressed, a normally open switch positioned to be actuated by said first striker to close said switch while said first push button is depressed, a switch contact secured to said shaft, and a pair of contacts positioned to be bridged by said switch contact when said shaft is in said second position.

4. An electric switch system comprising a shaft rotatable from a first position to a second position, an arm secured to said shaft, a first push button and a first striker positioned to engage said arm and rotate said shaft from said first position to said second position when said first push button is pressed, a second push button and a second striker positioned to engage said arm and rotate said shaft from said second position to said first position when said second push button is pressed, a normally open switch positioned to be actuated by said first striker to close said switch while said first push button is depressed, a first switch contact secured to said shaft, a first pair of contacts positioned to be bridged by said first switch contact while said shaft is in said second position, a second switch contact secured to said shaft, and a second pair of contacts positioned to be bridged by said second switch contact while said shaft is in said first position.

JAMES E. McNIEL.
